GEORGE H. WEIDEMANN AND HORACE E. KELLEY, OF MIDLAND, MICHIGAN, ASSIGNEES
TO THE DOW CHEMICAL COMPANY, OF MIDLAND, MICHIGAN, A CORPORATION OF
MICHIGAN

FOUNDRY LADLE

Application filed August 31, 1932. Serial No. 631,226.

The present invention relates to a ladle for dipping molten metal from a body thereof and transferring the same to a mold or other apparatus. While the invention is applicable to general use in the foundry, it is especially applicable to the handling and pouring of readily oxidizable metals, such as magnesium and the alloys thereof.

The term "magnesium" or "magnesium alloy" used herein and in the appended claims means pure magnesium or an alloy thereof containing 50 per cent or more of magnesium.

According to conventional foundry practice, molten metal is transferred from the melting equipment to the molds by means of an open vessel or ladle. Conventional ladles for the purpose consist essentially of a vessel of suitable size to hold the molten metal, having a pouring lip at the rim thereof. In some of these a skimmer is provided at the pouring lip to prevent floating impurities, such as dross or slag, from running out with the molten metal; in others, the metal is discharged from an opening in the side or bottom of the ladle. Such ladles may be provided with a handle or mounted on trunnions or supported by a bail.

When such ladles are used with molten magnesium, they are not wholly satisfactory inasmuch as a number of special problems arise in connection with the melting, handling, and pouring of such readily oxidizable metal. For example, in the conventional methods for melting magnesium, a flux is used with the metal in the melting pot. The flux acts not only to collect the impurities from the metal with which it is in contact, but also to form a protective covering over the metal which excludes the atmosphere and prevents oxidation or burning. Two general types of fluxes are so employed. The one type is a semi-fluid mixture composed usually of molten alkali and alkaline earth metal salts thickened with alkaline earth metal oxides and fluorides. The other type is a highly mobile fused mixture consisting principally of alkali and alkaline earth metal salts such as sodium chloride and magnesium chloride. The specific gravity of the latter type of flux is regulated in some instances by

the addition of a relatively small proportion of barium chloride, so that the metal floats in the molten mixture and at the same time the surface tension of the flux mixture is such that the top surface of the metal is more or less completely covered with a film of the molten fluid.

When it is attempted to withdraw molten magnesium from a melting pot some flux may become entrained with the metal in the ladle and, if the ladle be of a conventional type, some of the entrained flux will be discharged with the metal into the mold. The known bottom or side pouring spouts or surface skimming attachments of conventional ladles are ineffective to retain in the ladle the highly mobile molten constituents of the fluxes owing to their tendency to flow with the metal. The molten mobile fluxes creep or flow in the interface between the walls of the ladle and the body of molten metal therein and such creeping is aided by the motion of the molten metal as it passes over the surface when poured from the ladle. Thus it becomes practically impossible to pour a casting that is free from flux inclusions using a conventional type of ladle for dipping the molten magnesium from a flux covered body thereof.

One of the objects of the present invention is to provide a ladle suitable for transferring molten magnesium from a flux covered body thereof to a mold such that it prevents flux or other impurities, which may enter the ladle when the molten metal is dipped therewith, from being discharged with the molten metal. Other objects and advantages will appear as the description proceeds.

To the accomplishment of the foregoing and related ends, the invention, then, consists of the apparatus hereinafter fully described and particularly pointed out in the claims, the annexed drawing and the following description setting forth in detail certain means of carrying out the invention, such means illustrating, however, but several of the various ways in which the principle of the invention may be used.

In said annexed drawing:—

Fig. 1 is a vertical central section through

our improved ladle. Fig. 2 is a plan view of our improved ladle.

In the present invention an open top vessel of suitable capacity is employed which constitutes the body of the ladle. A guard is provided on the upper rim on the pouring side which extends over a portion of the top of the vessel so that the ladle may be tilted about its axis in the pouring plane as much as 100° without discharging metal over the guard. By locating a tubular subsurface pouring spout in the upper rim of the guarded side of the vessel or in the guard thereof near said upper rim, so that said tubular spout extends obliquely toward the bottom thereof in such manner as to be out of contact with the walls thereof, any flux which may be picked up in the ladle comes in contact with the walls of the pouring spout only near its upper end when the filled ladle is tilted, we may substantially prevent the discharge of flux-contaminated metal from the ladle.

Referring to the drawing, 1 is a fluid tight vessel of suitable capacity, 2 is a pouring tube or spout extending downwardly into the vessel at an angle with the wall thereof. Spout 2 is sealed through the liquid tight guard 3 at the top of the vessel, but does not touch the side walls thereof. A sweep 4 is attached to the outside of the vessel near the rim thereof and diametrically opposite to the pouring spout while a handle 5 is provided for manipulating the ladle. When the capacity of the vessel is too great for hand manipulation, trunnions may be substituted for the handle. These may be located on the walls of the vessel as indicated at 6. In some cases it may be preferable to employ a handle, as indicated, together with a bail. The space provided between the inlet end 10 of the pouring tube 2 and the bottom corner 11 of the vessel is sufficient to permit impurities to gather, so that they will not be drawn into the pouring tube when the ladle is tilted during pouring.

The essential elements of our new and improved ladle comprise a vessel, a pouring tube located at its upper end near the rim of the vessel and depending therein towards the bottom and out of contact with the walls thereof and a guard covering a portion of the top of said vessel so that metal may be discharged through the pouring spout from the ladle when tilted.

The whole of the ladle above described may be constructed from a metal having a high melting point and which does not alloy with magnesium. Iron or steel is well suited for the purpose, and the individually indicated parts may be assembled readily by welding.

Our improved ladle may be used in the following manner in connection with the transfer of molten magnesium from a flux covered molten body thereof to a mold:—The

flux or impurities floating upon the surface of molten metal in a melting pot is swept aside by means of the sweep 4 to expose an area of clean metal in which to submerge and fill the ladle. After filling, a portion of the metal may be poured back into the melting pot so as to rinse out of the pouring spout oxide or other impurities which may collect therein. The molds are then poured promptly, care being taken to stop pouring before the pouring spout becomes uncovered by metal. In this way flux which may be dipped up accidentally with the molten metal in the ladle does not come in sufficient contact with the pouring tube during pouring to creep down along the surface thereof so that it would be carried along with the stream of metal and find its way eventually into the casting.

In order to show the effectiveness of our improved ladle over those conventionally employed, the following tests were conducted.

Test 1

A quantity of magnesium alloy consisting of approximately 94.7 per cent magnesium, 5 per cent aluminum, and 0.25 per cent manganese was melted down in a bath of magnesium chloride-sodium chloride flux. A conventional bottom pouring ladle was then used to dip metal out of the melting pot by first brushing aside as much of the flux as possible and then dipping metal out of the pot from the area exposed. The metal was then poured from the ladle into a cylindrical billet mold and allowed to solidify. After solidification the billet, weighing approximately 70 pounds, was machined to remove the outer skin and then subjected to examination for defects. The machined surface showed a number of holes filled with flux. The billet was then radiographed which showed that there were flux inclusions distributed throughout the casting. This was further verified by cutting the casting into sections and on visually inspecting these sections flux inclusions previously shown by the radiograph were plainly visible.

Test 2

A similar billet was cast from a similar body of molten metal protected in flux as in Test 1, but instead of using a conventional ladle we used our improved type, such as illustrated. After the billet had solidified, it was machined to remove the outer skin and then subjected to the same examinations as in the previous test. The result of these observations showed that the surface of the billet was free from flux inclusions. The interior of the billet, as shown by radiographs and by a visual inspection of sections cut therefrom, was entirely free from flux inclusions.

Test 3

Using our improved ladle, the flux was pushed back from the surface of the metal in the melting pot and as before a ladle of metal was withdrawn therefrom. A quantity of flux of the same composition as was used in the melting pot was then poured onto the surface of the molten metal in the ladle and then a similar billet was cast by pouring the metal from the ladle into the billet mold while the flux remained in the ladle. After casting, the outside skin of the billet was machined off and then the billet was examined for defects. The machined surface was entirely free from flux holes, and the interior, as examined by the radiograph and by a visual inspection of sections cut therefrom, was entirely free from flux inclusions. These tests show that when some flux is inadvertently admitted to our improved ladle the long surface of travel over which such flux must necessarily pass before it can be discharged therefrom prevents the entrainment thereof with the molten metal and so prevents flux inclusions in the casting.

The invention is also especially valuable since any type of impurity that is separable from the metal by gravity, such as oxide or flux, which tends to accumulate either in the bottom of the ladle or on the metal surface or both while the metal is being poured therefrom, cannot be discharged from the ladle during such an operation. Therefore, our new ladle provides a means of preventing simultaneously not only floating impurities, but also settled impurities from entering the casting.

This application is a continuation in part of our prior application Serial No. 512,908, filed February 2, 1931.

Other modes of applying the principle of our invention may be employed instead of those explained, change being made as regards the means herein disclosed, provided those stated by any of the following claims or their equivalent be employed.

We therefore particularly point out and distinctly claim as our invention:

50 1. In a ladle of the character described, the combination of an open top vessel, a liquid tight guard attached to the rim thereof and extending part way over the top of said vessel, a tubular subsurface pouring spout sealed through the guarded rim of said vessel and extending downwardly therein at an angle with the wall thereof.

60 2. In a ladle of the character described, the combination of an open top vessel, a liquid tight guard attached to the rim thereof and extending part way over the top of said vessel, a tubular subsurface pouring spout sealed through the guarded rim of said vessel and extending downwardly therein at an angle with the wall thereof, and a sweep at-

tached to the wall of the vessel at a point near the rim and diametrically opposite to said pouring spout.

Signed by us this 24 day of August, 1932.

GEORGE H. WEIDEMANN.
HORACE E. KELLEY.
